UNITED STATES PATENT OFFICE.

SVEN G. BOLIN, OF KANSAS CITY, MISSOURI.

METAL DOOR.

1,104,868.

Specification of Letters Patent. Patented July 28, 1914.

Application filed February 6, 1913. Serial No. 746,466.

To all whom it may concern:

Be it known that I, SVEN G. BOLIN, a subject of Sweden, residing at Kansas City, in the county of Jackson and State of Missouri, have invented certain new and useful Improvements in Metal Doors; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to metal doors, and has for its principal object to provide a door of that type comprising a removable panel and rail and stile construction whereby the panel may be applied to or removed 20 from the door to facilitate the initial installation or replacement of the panel.

It is also an object of the present invention to provide a metal door, having a removable panel, with means for locking the 25 panel in place and which may be easily applied to or removed from panel inclosing parts. In accomplishing this object I have provided the details of structure herein-after described and illustrated in the accompanying drawings, wherein:

Figure I is a perspective view of a metal door constructed according to my invention, a portion being removed to illustrate the inner structure. Fig. II is a vertical sectional view of a portion of the door, taken on the line II-II, Fig. I. Fig. III is a detail view of the beading key. Fig. IV is a sectional view of one of the vertical side members before the key is in place. Fig. 40 V is a similar view showing the key in position. Fig. VI is a detail view showing the method of finishing the bottom of the door.

Referring more in detail to the parts: 1 designates the stiles, 2 the end rails, and 3 the center rail of a metal door embodying 45 my improvements; each of the stiles and rails being provided with ornamental edges or molding 4 in order to enhance the appearance of the door and provide thickness 50 for the accommodation of the key parts hereinafter described.

5 designates a panel which is located between the end and center rails 2, 3, and, as it is usually made of the same material as 55 the body of the door, need not be adapted for removal, although it may be attached to

the rails and stiles by the keys used for mounting the upper panel, if so desired. In order, however, to make the construction of all of the stiles and rails uniform, 60 I prefer to equip each with the interlocking beading constructed according to my invention. In making stiles and rails of this type, each part has mating beads, each of which comprises an inturned panel face 7 65 having a back turned shoulder 8 and a lip 9 parallel with the panel face, the inturned parts being bent back to form a diverging mouth within the stile, or rail, as illustrated most clearly in Fig. IV.

In installing the lower panel the panel 70 may be projected between the inturned parts of the lips of some of the rails and stiles before the other parts are applied, as it is not necessary to provide for removing said 75 lower panel. With the panel in place a key 10 is moved over the shoulders and lips of the inturned panel faces of the molding to draw same together and firmly against the panel, the key preferably comprising a rail 80 11 which is adapted to seat on the shoulders 8 and form a base against which the edge of the panel may abut, the arms 12, which overlie the ends of the lips 9 and tongues 13 which project over the shoulders and hold 85 the key to the panel parts.

In order to provide for the installation 90 of the upper panel, after the rails and stiles have been completely assembled, and for replacement of said panel after the door has been in use, I provide the upper rail with a slot 14, the material at the edges of which is turned down to form a shelf 15 for supporting an inlay cap 16 which may be screwed to the shelf after the panel has 95 been positioned, in order to completely close the rail. With this construction, keys may be applied to the middle and side rails before the panel is inserted. With the bottom and side keys in place, the panel may be projected through the upper opening 14 so that it will slip to its place between the rail and stile beadings. After the panel is in place the inlay cap may be fixed to the upper edge of the top rail and the key 10 projected 100 through an opening 17 in the edge of one of the stiles to clamp over the inset beading parts to hold the removable panel firmly in place.

In order that the opening 17 may be closed 110 without breaking the edge surface of the stile, I provide an inset flange 18 around

said opening upon which a cap 19 may seat and to which said cap may be secured.

One stile is provided with a reinforcing strip 20 which is exposed through apertures 5 21 and to which hinges (not shown) may be secured in any suitable manner.

The lower cross rail is provided with a channeled member 22 which is welded or otherwise secured to the sides thereof and 10 provided with inturned edges 23 for receiving a finishing strip 24.

In order to deaden the metallic sound, prevalent in doors of this type, I prefer to place strips of cork composition 25, or other 15 similar substance, between the sides of the stiles and cross rails.

It is apparent that with this construction the door may be completely assembled, except for the upper panel, and that the panel 20 may be set after the door has been erected in a building, thereby enabling such panels to be painted with the name of an occupant of an office before it is installed in a door and it is also possible to replace a glass 25 panel without removing the beading or separating the stiles from the rails.

Having thus described my invention, what I claim as new therein, and desire to secure by Letters-Patent, is:—

30 1. In a metal door, a rail having edge portions turned backwardly into the interior of the rail to form spaced panel faces, each provided with a laterally turned shoulder and inturned lip, a key having a rail portion seated against said shoulders between the lips, and having edge arms and tongues overlying the shoulders and lips, whereby the panel face portions of the rail are held in spaced relation and the key held to the in- 40 turned portions of the door rail.

2. In a metal door, a rail comprising panel beads, having inturned edges forming panel faces and having laterally turned shoulders and inturned lips at the inner edges of the 45 panel faces, a panel having an edge portion located between said faces, and a key slidably mounted on the shoulders and lips to clamp the panel faces of the door rail against said panel and form a seat therefor.

50 3. In a metal door, a rail comprising spaced beading members having mating bearing faces yieldingly tensioned oppositely and each provided with a laterally directed shoulder and offset lip, of a key having a 55 base adapted to seat on said shoulder between the lips, and arms for inclosing the

shouldered parts and holding same in locking position and against said seat, substantially as set forth.

4. In a metal door, a stile and rail construction comprising a single piece of sheet metal of substantially U-shaped cross section, having free ends beaded and turned inwardly to form a longitudinal slot, and creased to provide laterally directed shoulders and inturned lips, and a sliding key having a bead for holding said lips and shoulders in alinement and having arms for holding said lips and shoulders to said bead. 60

5. A metal door comprising stiles and 70 rails, one of which is provided with a slot and with spaced beading members, another of said parts with an opening arranged at right angles to the slot, a panel adapted for projection through the slot and between the 75 beading members to its position in said door, and a key adapted for projection through said opening and over the spaced beading members to clamp the latter against the panel, for the purpose set forth. 80

6. A metal door comprising stiles and rails, one of which is provided with a slot and with spaced beading members and another of said parts with an opening arranged at right angles to a slot, a panel 85 adapted for projection through the slot and between the beading members to its position in said door, a key adapted for projection through said opening and over the spaced beading members to clamp the latter against 90 the panel, and caps adapted for closing the slot and key openings.

7. A metal door comprising stiles and rails, one of which is provided with a slot and with spaced beading members, another 95 of said parts with an opening arranged at right angles to the slot, a panel adapted for projection through the slot and between the beading members to its position in said door, a key adapted for projection through said 100 opening and over the spaced beading members to clamp the latter against the panel, flanges surrounding said slot and key openings, and caps adapted for seating on said flanges and for attachment to the door parts 105 to cover said openings.

In testimony whereof I affix my signature in presence of two witnesses.

SVEN G. BOLIN.
